(57) CLAIM

I claim the ornamental design for the eraser, as shown and described.

DESCRIPTION

FIG. 1 is a perspective view of the eraser;

FIG. 2 is a side view of the eraser;

FIG. 3 is a rear view of the eraser;

FIG. 4 is a front view of the eraser;

FIG. 5 is a top view of the eraser; and,

FIG. 6 is a bottom view of the eraser.

The broken lines showing the inside of the four circles on the handle in FIG. 2 are included for the purpose of illustrating environment and form no part of the claimed design.
